The ornamental design for a two handle faucet spout cap, as shown and described.

DESCRIPTION

FIG. 1 is a top perspective view of a two handle faucet spout cap showing my new design;

FIG. 2 is a front elevational view thereof;

FIG. 3 is a side elevational view thereof;

FIG. 4 is a top plan view thereof;

FIG. 5 is a front elevational view of a second embodiment of the two handle faucet spout cap differing from that illustrated in FIG. 1 in having four flats instead of two flats;

FIG. 6 is a side elevational view of the second embodiment illustrated in FIG. 5;

FIG. 7 is a top plan view of the second embodiment;

FIG. 8 is a cross-sectional view taken along line 8—8 in FIG. 4;

FIG. 9 is a front elevational view of a third embodiment of the two handle faucet spout cap, differing from that illustrated in FIG. 1 in having eight flats instead of two flats;

FIG. 10 is a side elevational view of the third embodiment illustrated in FIG. 9;

FIG. 11 is a top plan view of the third embodiment;

FIG. 12 is a top plan view of a fourth embodiment of the two handle faucet cap, differing from that illustrated in FIG. 1 in having six flats instead of two flats; and,

FIG. 13 is a side elevational view thereof.

The broken line showing of the faucet and handles in FIG. 1 is for purposes of illustration only and forms no part of the claimed design.
